GOLF CLUB HEAD

William N. Beveridge, Wauwatosa, Wis.

Application December 29, 1952, Serial No. 22,914

Term of patent 14 years

(Cl. D34—5)

To all whom it may concern:

Be it known that I, William N. Beveridge, a citizen of the United States, residing at Wauwatosa, in the county of Milwaukee and State of Wisconsin, have invented a new, original, and ornamental Design for a Golf Club Head, of which the following is a specification, reference being had to the accompanying drawing forming a part thereof.

Fig. 1 is a front elevational view of a golf club head, showing my new design;

Fig. 2 is a rear elevational view thereof; and
Fig. 3 is an end elevational view thereof.

The broken line showing of the club shaft is for the sake of illustrative purposes only.

I claim:

The ornamental design for a golf club head, as shown and described.
